UNITED STATES PATENT OFFICE.

ROBERT LEE COOPER, OF MIDDLETOWN, OHIO, ASSIGNOR TO THOMAS SEBALD, OF MIDDLETOWN, OHIO.

KEY-RING HOLDER.

1,414,181.

Specification of Letters Patent. Patented Apr. 25, 1922.

Application filed August 11, 1921. Serial No. 491,482.

To all whom it may concern:

Be it known that I, ROBERT LEE COOPER, a citizen of the United States, residing at Middletown, in the county of Butler and State 5 of Ohio, have invented certain new and useful Improvements in Key-Ring Holders; and I do declare the following to be a full, clear, and exact description of the invention, such as will enable others skilled in the art 10 to which it appertains to make and use the same.

This invention relates to an improved device which can be conveniently termed a holder for key-rings.

15 The principal object of the invention is to provide a device of this class which embodies belt engaging means including closed loops through which the belt passes, together with a clip which is carried by the means, 20 this clip being such that it permits a key-ring to be detachably connected therewith and has a portion thereof bearing against the belt to bind the latter against the loops in such a way as to prevent loss of the belt 25 engaging means off of the belt when the ends of the belt are separated.

Another object of the invention is to provide a device of this class wherein each belt-engaging device is formed from a small 30 piece of tubing which is flattened and has a portion cut out to provide the aforesaid loops through which the belt passes, thus providing a device which is extremely advantageous from the manufacturer's view- 35 point, and is inexpensive.

Other objects and advantages of the invention will be apparent during the course of the following description.

In the accompanying drawings forming a 40 part of this specification and in which like numerals are employed to designate like parts throughout the same:

Figure 1 is a front elevational view of a key ring holder constructed in accordance 45 with this invention showing the same attached to a section of a person's belt.

Figure 2 is a sectional view taken substantially on the plane of the line 2—2 of Fig. 1.

50 Figure 3 is a rear elevational view of the device.

Figure 4 is a view like Fig. 1 showing a slightly modified form of the invention.

55 Figure 5 is a rear elevational view of this form of the invention.

Figure 6 is a sectional view taken substantially on the plane of the line 6—6 of Fig. 4.

Referring to the drawings, 1 designates generally the belt engaging device, 2 designates the spring clip or retainer for the key ring R, and B designates a portion of a person's belt. In forming the belt engaging device 1, I employ a length of tubing cut into substantially rectangular pieces and flattened so that it assumes the elongated substantially oval shape shown in the drawings. Then, I cut away a portion of this material leaving side portions 3 and a central connecting portion 4. The side portions 3 provide what may be conveniently termed loops for passage of the belt, while the portion 4 serves as a connection for these loops. The portion 4 also serves as a means to permit attachment of one end of the 70 spring clip 2 thereto. It is to be stated here that this spring clip is simply formed from a band which is permanently secured at one end to the portion 4 as indicated at 5, being bent intermediate its ends as indicated at 6 75 and having its opposite end bent upwardly and spaced slightly away from the front face of the member 1 as indicated at 7. The extremity of this end of the band which is free, is bent upon itself as indicated at 8 80 and provides a restricted entrance for the key ring R. It is to be noted that the bend 6 is disposed below the edge of the belt 1 and thus provides sufficient space between the latter and band to accommodate the key- 85 ring after it has been pulled downwardly between the portion 7 of the band and front face of the member 1. At this point I wish to direct attention to the fact that the band 90 which serves to form the key-ring clip is bent at the point 9 so as to space it slightly away from the inner face of the member 1 and it will be seen that when the belt is passed through the loops, this bent portion 9 will serve to bind the belt tightly against the loops and will prevent slippage of the device 1 off of the belt even after the ends of the belt are separated.

It has been previously indicated that the forms of the invention shown in Figs. 4 to 6 95 are slight modifications. By referring to these figures it will be seen that the parts of the device are substantial duplicates of the parts above described with the exception that the clip for retaining the key ring 100 ring 110

in place is not bent upon itself as indicated in Figure 2 but is straight and the extremity of the free end thereof is flared outwardly as indicated at 8^a to facilitate insertion of the key-ring between the clip and belt-engaging device. Otherwise, this form of the invention is the same as that described and therefore the same reference characters will apply to all like parts in both forms of the 10 invention.

In use, the device 1 is placed upon the belt and slid to the desired position, being retained in place by the bend 9 of the retaining clip 2. While the clip serves to retain 15 this device 1 against slippage, it permits it to be gripped by hand and easily and readily moved to the desired point or be entirely removed from the belt whenever desired. It 20 is hardly necessary to state that the key ring R is slipped between the free end 8 of the clip 2 and is forced between the latter and part 1 until it is allowed to seat in the bend 6 below the part 1 where it can be rotated to permit the keys to be attached and detached.

25 By carefully considering the description in connection with the drawings, persons familiar with devices of this class will doubtless be able to obtain a clear understanding of the invention. Therefore, a 30 more lengthy and detailed description is deemed unnecessary.

Since probably the best results may be obtained with the construction and arrangement herein shown and described, this is

taken as the preferred embodiment of the 35 invention. However, I wish it to be understood that minor changes coming within the scope of the subjoined claims may be resorted to if desired.

40 I claim:

1. A key ring holder comprising a belt engaging device having a closed loop for passage of the belt, and a spring key ring clip secured at one end to said device, its opposite end being free, said clip being bent 45 intermediate its ends and below the lower edge of said device for forming a seat for reception of the key ring, being also bent above and adjacent said seat to form a portion for engaging and forcing the belt into 50 frictional contact with said loop for preventing accidental slippage of the device on the belt.

2. A key ring holding device comprising a belt-engaging member including a pair of 55 closed loops for passage of the belt and a flat portion connecting said loops together, a key ring clip formed from a strip of resilient metal, said strip being secured at one of its ends to the inner flat face of said connecting portion and being bent between its ends at a point below the lower edge of the latter and then bent upwardly along the front face thereof and having its free end 60 bent to facilitate insertion of the key ring.

65 In testimony whereof I have hereunto set my hand.

ROBERT LEE COOPER.
